(57) **CLAIM**

I claim the ornamental design for a wand body massager, as shown and described.

DESCRIPTION

FIG. 1 is a perspective view of a wand body massager. FIGS. 2 and 3 are left and right side views, respectively, of the wand body massager.

FIG. 4 is a front view of the wand body massager.

FIG. 5 is a rear view of the wand body massager.

FIG. 6 is a top view of the wand body massager; and,

FIG. 7 is a bottom view of the wand body massager.

The broken lines are directed to environment and are for illustrative purposes only; the broken lines form no part of the claimed design.
